UNITED STATES PATENT OFFICE.

MARTIN CHRISTENSEN, OF ELMHURST, ILLINOIS, ASSIGNOR TO THE CHRISTENSEN MACHINE COMPANY, OF RACINE, WISCONSIN, A CORPORATION OF WISCONSIN.

STITCHING APPARATUS.

Application filed January 2, 1926. Serial No. 78,926.

The invention relates to book-stitching machines, and more particularly to the stitching apparatus for such machines.

Heretofore machines have been of two distinct types, to wit: the saddle-stitch type and the side-stitch type, so that two separate and distinct machines had to be provided to accommodate the different kinds of work of the bookmaker. One of the objects of this invention is to provide a stitching apparatus wherein the same stitcher may be used to stitch books either of the saddle-stitch type or the side-stitch type.

A further object of the invention is to provide book-stitching apparatus in which the stitching mechanism is adapted either for saddle-stitch or side-stitch books, and one feeding mechanism suffices for both kinds of work.

20 The invention further consists in the several features hereinafter set forth and more particularly defined by claims at the conclusion hereof.

In the drawings, Fig. 1 is a side elevation view of the stitching apparatus embodying the invention, with parts of the signature-supporting table and feeding mechanism shown in section;

25 Fig. 2 is a detail view showing the position of parts of the stitching mechanism for one type of work;

Fig. 3 is a front elevation view of one of the stitching units;

Fig. 4 is a rear elevation view of this unit.

30 In the drawings the numeral 5 designates a part of the framework of the machine, and 6 the signature-supporting saddle designed to support the stitchers for saddle-stitch work, in the usual manner, and also 40 provided with a longitudinally extending ledge or support 7 designed to support signatures for side-stitch work. This saddle, it will be understood, is suitably associated with the frame of the machine, and feeding mechanism of any suitable type is associated with that side of the saddle provided with the ledge 7. This feeding mechanism may be of the type shown in my prior United States Patent No. 1,400,725, dated December 20, 1912, or of the type of machine shown in my copending application, Serial No. 78927, filed January 2, 1926. In either case the feeding mechanism embodies an intermittently longitudinally reciprocating feeding bar 8, and this may be reciprocated as shown

and described in my prior United States Patent No. 1,351,231, dated August 31, 1920. As shown, the cooperating part of the feeding mechanism embodies a plurality of spring-pressed fingers 9, one only of which is shown, which are intermittently reciprocated and cooperate with the feed bar 8 to move the assembled groups of signatures along the saddle, either when the signatures are arranged for saddle stitching or when arranged to have their edges abut against the ledge 7. As the particular feeding mechanism forms the subject-matter of my prior patent and of the application above referred to, further detailed description thereof is not considered necessary, inasmuch as for the purpose of this invention any suitable feeding mechanism associated with the saddle for saddle-stitch and side-stitch books may be used with the stitching apparatus hereinafter described.

While the stitching apparatus usually embodies stitching units arranged in pairs, only one of such units has been shown for the purpose of explaining the invention, other units acting in the same way as the one to be described.

Each stitching unit comprises a stitcher-carrying frame 10 which is pivotally mounted on a pin 11 carried in the forked portions 12 of the frame 5 so that it may swing relative to the frame. The frame 10 has a hollow tubular portion 13 in which a tubular portion 14 of the stitcher head 15 is slidably mounted and adapted to be held in locked position relative to the portion 13 by means of a set-screw 16. The stitcher head 15 is provided with the usual stapling mechanism which is driven from a shaft 17 carrying a bevel gear 18 and meshing with another bevel gear 19 in the stitcher head which is mounted on a shaft 20. When the stapling mechanism is in an upright position for cooperation with the clincher mechanism hereinafter described for functioning as a saddle-stitch type of stitching apparatus, the shaft 20 is driven from a drive shaft 21 through a series of gears. As shown, a gear 22 on the shaft 21 meshes with an adjustable idler gear 23 journaled on a shaft 24; the gear 23 in turn meshes with a gear 25 journaled on the shaft 26 which in turn meshes with a gear 27 on a shaft 28, which in turn meshes with a gear 29 on a shaft 30, which in turn meshes with a gear 31 on a

shaft 32, which in turn meshes with a gear 33 on a shaft 34, which also meshes with a gear 35 on a shaft 36, and the gear 35 meshes with a gear 37 on the shaft 20. The shafts 5 24, 26, 28, 30, 32, 34 and 36 are stud shafts secured to the tubular member 14, and the gears mounted thereon constitute a transmission mechanism between the gears 23 and 37 so that with the gearing above described 10 the stitcher-drive-shaft 17 is driven from the main drive-shaft 21 when the stitcher is arranged in the upright position.

For side-stitch work, that is, where the staples pass through a group of signatures 15 arranged to move along one side of the saddle adjacent the ledge 7, the stitching apparatus is designed to be swung from the full line position to the dotted line position shown in Fig. 1. When the stitching mechanism 20 is thus swung to the dotted line position the gearing 23 is adjusted so as to mesh directly with the gear 37, as shown more particularly in Fig. 2, so that the drive for the stitcher shaft 17 is then 25 through the gear 22 on the shaft 21 to the gear 23 and thence to the gear 37 journaled on the shaft 20. From Figs. 1 and 2 it will be noted that the stud shaft 24 for the gear 23 is mounted in an arcuate slot 38 in 30 a stationary member 39 and is locked in position by a nut 40. The stitcher frame 10 is also locked in an adjusted position in either instance by means of a link 41 which at one end is clamped to the frame 39 by the nut 40 and at the other end clamped to the shaft 26 or to the shaft 20; in one instance by a nut 42 and in the other instance by a bolt 43 designed to engage a threaded opening 44 in shaft 20. When the 35 stitcher is in an upright position the shaft 24 is at one end of the slot 38, and when the stitcher has been swung to the dotted line position, as shown in Fig. 2, the shaft 24 has been moved to the other end of the slot 38, it being understood, of course, that in changing the position of the stitcher from the full line position to the dotted line position the outer end of the link 41 is removed from the shaft 26 and connected 40 with the shaft 20.

In changing the position of the stitcher from the full line position to the dotted line position, it is necessary to have the stitcher head clear the feeding mechanism, and for 45 this purpose the tubular portion 13 of the frame is provided with a slot 16 whereby upon the loosening of the set screw 16 the tubular portion 14 of the stitcher head may be pulled out to such an extent as to have 50 the parts of the stitcher head clear the feeding mechanism and thereafter be pushed back and secured in position by the setscrew 16 when the stitcher head has assumed the dotted line position.

55 The detailed construction of the clincher

mechanisms for association with the stitcher head are well known. The present invention has to do with the drive for the clincher mechanism to permit of the two types of work. As shown, a clincher device 45 has its operating rod connected at 60 to one arm 47 of a lever 48 which is pivotally mounted on the shaft 11 between parts 49 of the stitcher frame 10. The other bifurcated arm 50 of said lever 48 is 65 operatively connected by a pin 51 to the actuating member 52 of another clincher mechanism 53 so that both clincher mechanisms are actuated through the swing of the lever 48. For oscillating the lever 48 so as 70 to actuate the clinchers 45 and 53, an arm or lever 54 is secured to the shaft 11 so as to oscillate the same, and is connected by a pin 55 to a link 56 operatively connected 75 by a pin 57 to a cam-operated lever 58 pivoted intermediate its ends at 59 and carrying a roller 60 engaging a cam 61 driven by the shaft 21. With this construction, when the stitcher is in the full line position 80 the rotation of the cam 61 causes an oscillation of the lever 58 in proper timed relation with the stapling mechanism so as to swing the lever 48 through the connections 85 above described to operate the stapling device 45 so that the staples are clinched 90 in the groups of signatures passing along the inverted V-shaped saddle. When the stitcher head is swung to the dotted line position 95 and the cam 61 is rotated to actuate the lever 58, the lever 48 is oscillated as in the first set-up, but in this instance the stitcher head is now in a position to cooperate with 100 the mechanism 53 so that this clincher now becomes effective and the signatures which pass along one side of the saddle adjacent 105 the ledge 7 are stitched.

From the foregoing description it will be observed that I have provided a stitching apparatus wherein either saddle or side type stitching may be accomplished on the same machine and with a single feeding mechanism.

I desire it to be understood that this invention is not to be limited to any particular form or arrangement of parts except in so far as such limitations are specified in the claims.

What I claim as my invention is:

1. In a book-stitching machine, stitching mechanism including stapling mechanism movable to a position to saddle-stitch a group of signatures and to a position to side-stitch a group of signatures, and means for operating said stapling mechanism.
2. In a book-stitching machine, the combination of stitching mechanism including stapling mechanism having a plurality of stitching positions and movable to said positions for different types of stitching, means for driving said stapling mechanism in

either of its stitching positions, and signature-carrying means operable to convey the signatures past said stitching mechanism in either of its stitching positions, said stapling

6 mechanism being movable to either of its stitching positions without interfering with said signature-carrying means.

3. In a book-stitching machine, the combination of a support for carrying a straddled group of signatures or a group of signatures on one side thereof, signature-conveying means operable to carry either arrangement of signatures along said support, stitching mechanism including stapling 10 mechanism adapted to be moved to operate on either arrangement of signatures to respectively produce either a saddle-stitched or a side-stitched book, clincher mechanisms 15 respectively cooperating with said stapling mechanism in its operating positions, a common actuating means for said clincher mechanisms, and means for driving said stapling mechanism in either of its stitching positions.

20 25 4. In a book-stitching machine, the combination of a support for carrying a straddled group of signatures or a group of signatures on one side thereof, signature-conveying means operable to carry either arrangement of signatures along said support, stitching mechanism including stapling mechanism swingable to a position to operate on either arrangement of signatures to respectively produce either a saddle-stitched 30 or side-stitched book, clincher mechanisms 35 respectively cooperating with said stapling mechanism in its operating positions, a common actuating means for said clincher mech-

anisms, and means for driving said stapling mechanism in either of its stitching positions.

5. In a book-stitching machine, the combination of a support including a saddle for carrying a straddled group of signatures or a group of signatures on one side thereof, signature-conveying means, stitching mechanism including stapling mechanism movable to a position to operate on a straddled group of signatures or on a group of signatures on one side of the saddle, a clincher 45 mechanism operable through the apex of said saddle and cooperating with said stapling mechanism in one of its positions to saddle-stitch a group of straddled signatures, clincher mechanism operable through 50 one side of said saddle and cooperating with said stapling mechanism in the other of its positions to side-stitch a group of signatures, and means for driving said stapling mechanism in either of its operating 55 positions.

6. In a book-stitching machine, the combination with a support, of signature-supporting means and signature-feeding means for either saddle-stitch or side-stitch grouping 60 of signatures, stitching mechanism including stapling mechanism operable on either arrangement of signatures and including an extensible head swingable relative to said support and extensible during its shifting 65 from one of its operating positions to the other to clear said feeding means, and means for operating said stapling mechanism.

In testimony whereof, I affix my signature.

MARTIN CHRISTENSEN.
